UNITED STATES PATENT OFFICE.

WILLIAM GAAIKEMA, OF MUSKEGON, MICHIGAN, ASSIGNOR TO MOON DESK CO., OF MUSKEGON, MICHIGAN.

DESK.

No. 851,659.

Specification of Letters Patent.

Patented April 30, 1907.

Application filed February 28, 1906. Serial No. 303,481.

To all whom it may concern:

Be it known that I, WILLIAM GAAIKEMA, a citizen of the United States, residing at Muskegon, in the county of Muskegon and State of Michigan, have invented a new and useful Desk, of which the following is a specification.

This invention relates to desks and cabinets of that general class employed for the support of typewriting machines.

The object of the invention is to provide means whereby a typewriter support and elevating means therefor may be securely locked when the support is pulled forward and upward out of the cabinet or desk and will be disengaged from the locking devices on and by the initial movement of the supporting means to allow the latter to be lowered and pushed back into the cabinet.

20 The invention also comprises novel means for locking the typewriter support in the retracted position in the desk or cabinet against the action of a spring-actuated elevating means for the said typewriter support.

25 With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from 35 the spirit or sacrificing any of the advantages of the invention.

In the accompanying drawings:—Figure 1 is a sectional elevation of a typewriter desk or cabinet constructed in accordance with the 40 invention, the machine supporting table being shown in elevated position. Fig. 2 is a similar view, showing the table concealed within the cabinet. Fig. 3 is a detail perspective view of the machine supporting table and spring elevated frame, detached. Fig. 4 is a sectional elevation through a portion of the table and frame, showing the locking device for preventing movement of the frame until the machine supporting table has 45 been pulled out. Fig. 5 is a detail view on an enlarged scale of one of the frame elevating springs and its connections. Fig. 6 is a sectional view, illustrating a slightly modi-

fied construction. Fig. 7 is a transverse sectional view of the same on the line 7—7 of 55 Fig. 6. Fig. 8 is a view corresponding to Fig. 1 and illustrates a spring elevated frame of simple construction.

Similar numerals of reference are employed to indicate corresponding parts throughout 60 the several figures of the drawings.

The desk proper may be of any suitable construction, and preferably is provided with a permanent top 11 that extends over a chamber 12 in which the typewriter or other 65 machine and its support are concealed when inoperative position, and at the front is a sliding curtain 15 which may be drawn down to position shown in Fig. 2 in order to exclude dust and dirt. 70

The opposite side walls of the chamber 12 are provided with cam grooves, each groove having a straight horizontal portion 16 and an inclined portion 17, and said cam grooves may be conveniently formed by attaching 75 suitable wooden strips 18 to the vertical walls of the chamber 12.

Arranged within the chamber is a spring elevated frame of the construction best shown in Fig. 3. This frame includes a pair 80 of parallel side bars 20 and 21 connected by transversely extending end bars 22 and 23, and is supported by a series of pivotally connected levers, there being three levers 25, 26 and 27 at each side of the frame. The rear 85 ends of the levers 25 are connected to the side bars 20 and 21 by means of hinges 28, and the lower forward ends of said levers are provided with rollers 30 that are designed to travel on metallic track ways 32 which may 90 be formed of strips of metal placed at the bottom of the chamber 12. Each of the levers 25 carries a plate 33 that is provided with an opening for the passage of a spring actuated rod 35 which, also, extends through 95 the levers 25, the opposite ends of the rod being rigidly connected to the levers 26 by means of a transversely-disposed locking pin 36, or equivalent fastening devices.

At a point intermediate the ends of the rod 100 35 is arranged a revolvably adjustable collar 37 which may be locked to the rod by a pin 38 extending through openings formed in the collar, and an opening extending through the rod. This collar is provided with an arm 40 105 from which projects a pin 41 that forms a

bearing point for one end of a torsion spring 42 that is mounted on the rod 35, the opposite end of said spring engaging against a pin 43 that is carried by the plate 33. The function of the spring is to elevate the frame 20, and said spring, therefore, acts to move open or spread the levers from the position shown in Fig. 2 to that illustrated in Figs. 1 and 3. The collars 37 are provided with wrench engaging faces 45 so that they may be turned for the purpose of adjusting the stress of the springs, after which the pin 38 is passed through the openings of the collar and rod for the purpose of locking said collar in adjusted position.

The lower rear ends of levers 26 are connected by a transverse bar 46 in order to retain said levers in parallel relation, and the upper and lower ends of the levers are provided with anti-friction rollers 48 that are designed to travel on metallic wear strips secured to the bottom of the chamber 12 and to the lower surface of the side bars 20 and 21.

Extending through the sets of levers 25 and 27 is a rod 50, and said rod carries springs 42' which are connected to the rod and to the levers 27 in precisely the same manner as the lever opening springs of rod 35, and these springs tend to assist in moving the frame to elevated position. The upper ends of the levers 27 are arranged to enter locking notches 52 that are formed in the lower faces of the strips 20 and 21, and when so engaged, it becomes impossible to depress the frame, no matter what load may be added. These levers 27 are connected by a transversely extending rod 53 which serves to maintain the levers in parallelism.

To the rear ends of the bars 20 and 21 of the frame are secured blocks 54 carrying pins 55 in which small anti-friction rollers 56 are mounted that travel in the cam slots 16-17, and serve to guide the frame during its movement, and when these rollers are entered in the horizontal portions 16 of the slots, they serve to maintain the frame in its lowered position, while as soon as the frame is pulled out until the rollers arrive at the juncture of the straight and inclined portions of the slots, the elevating springs are free to act on the levers and move the frame upward.

The frame is provided with small anti-friction rollers 57 that extend through suitable slots formed in the bars 20 and 21 and serve as supports for a suitable table 58, the lower face of said table having wear strips 59 with which the rollers may engage. This table 58 carries a typewriter, sewing or other machine, and is provided with a pair of clamps 60, arranged to engage with the frame of the machine and hold the same firmly in place. The outer end of the slideable table is provided with an operating handle 61 which may be grasped for the purpose of moving the table into and from the cabi-

net, and it is essential that this table be moved either forward or rearward before the frame can move vertically.

To the bottom of the slideable table are secured two stop blocks 63 and 64 that preferably are provided with suitable buffers of yieldable material for engagement with the front and rear transverse bars of the frame, these stops serving to limit movement of the table in both directions.

The lower face of the slideable table 58 further carries a pair of cams 67, which during initial rearward movement of the table from the position shown in Fig. 1 will engage with and depress the cross bar 53 for the purpose of moving the ends of the levers 27 out of the notches 52, thus permitting downward movement of the frame, but until this slight backward movement of the table is accomplished, the frame is firmly and rigidly locked in elevated position. The rearward movement of the table is at this time limited by a pivotally mounted stop 70 that extends through a suitable slot formed in the frame bar 20. The rear end of the stop 70 is heavier than its forward end, so that it will normally be maintained by gravity in the position shown in Fig. 1, the forward end being disposed in the path of movement of the slideable table, and being arranged to engage the rear edge thereof when the table is moved and descends sufficient to permit its cam 67 to depress the cross bar 53, and no further rearward movement of the table can be accomplished until,

as the frame is depressed, the stop 70 engages against one of the levers 25, whereupon said stop is compelled to move to approximately horizontal position, and the table may then be slid to the rear. This locking of the table from rearward movement until the frame has been depressed, is of importance in that it prevents the typewriting or other machine coming into engagement with the fixed top 11 of the structure, and provision is, also, made for preventing the upward movement of the spring elevated frame until the slideable table has been first drawn out, so that the typewriting or other machine is prevented from engaging the desk top as the frame rises.

To accomplish this locking of the table and frame, the bar 21 of the frame is provided with an elongated lever 72, having two arms, of which the rear arm 73 is arranged to engage a locking dog or ear 74 at the lower rear portion of the chamber 12. The forward end of this lever has a cam shaped flange 75 that is disposed in the path of movement of a cam 76 that depends from the under side of the slideable table 58. It will be seen, on reference to Fig. 4, that the frame cannot be pulled out until the table is first moved outward, said table being drawn out to the dotted line position of Fig. 4 until the cam 76 engages the flange 75 of the locking lever and moves the same to release position, after which the

frame may be drawn out until the rollers 56 are at the juncture of the portions 16 and 17 of the slots, the springs then accomplishing the further upward and forward movement 5 of the frame:

In the construction illustrated in Figs. 6 and 7, the carrying rollers for table 58 have been omitted, and the table 58' is provided with a pair of cross bars 80 arranged to extend 10 down between the side bars of the rectangular frame, and provided with end tongues that fit within guiding grooves 81 formed in said side bars. In this case, also, the anti-friction rollers at the ends of the 15 spring elevated levers may be dispensed with.

In Fig. 8 is illustrated a simple construction of the device, in which the auxiliary levers 27 are dispensed with, and levers 26' are pivoted to the main levers 25' by the spring actuated rod. In this case the vertically movable frame constitutes the table on which the typewriting or other machine is supported, and at the sides of said frame are arranged 20 anti-friction rollers 83 for engagement with the inclined portions of the cam guiding slots, while the lower and inner ends of the levers 26' are provided with anti-friction rollers 84 that engage the horizontal portions 25 of the guiding slots. In this construction the upper forward ends of the levers 26' are arranged to enter locking notches formed in the lower face of the table or frame, and in order to release the same and permit lowering 30 of the frame, a suitable unlocking lever 86 is employed. The inner end of this lever 86 engages a cross bar 53' that is carried by the levers 26', while the outer end of the operating lever is arranged immediately under 35 the forward edge of the table or frame, so that when the lever is grasped, the releasing lever may be operated to withdraw the ends of the levers 26' from the notches, and permit downward movement of the typewriter 40 or sewing machine supporting table.

In the construction shown in Fig. 8, the top of the main casing or desk is provided with a hinged portion 11' which may be thrown back for the purpose of allowing the machine to move to operative position, and, 50 when the table is depressed, it may be locked by means of a hook 89, the latter being arranged to engage an eye 90 carried by the rear edge of the table.

I claim:

1. In a desk or like structure, interpivotable sets of spring-actuated levers carried by the desk, a frame carried by the interpivotable sets of levers with one set thereof engaging notches in the frame and thereby locking the latter in elevated position, a sliding table carried by said frame, and cams carried by said sliding table and positioned forward of said set of levers which engage the notches when the table is pulled forward and in elevated position, and adapted to disengage the levers from the notches on the initial rearward sliding movement of said table, to allow the lowering of the frame and table. 55

2. In a cabinet structure, a frame, spring-actuated supporting mechanism for elevating said frame and moving it out of the cabinet, a table slidingly mounted on the frame, a lever pivoted on the frame and having one end arranged to engage over an element in the cabinet structure to hold the frame depressed, a cam head on the other end of the lever, and a cam mounted on the slideable table and positioned to engage and depress said cam head, and thus disengage the other end of the lever, near the end of the forward sliding movement of said table to allow the said frame and table to rise. 70

In testimony that I claim the foregoing as my own, I have hereto affixed my signature 85 in the presence of two witnesses.

WM. GAAIKEMA.
